SETH E. STEVENTON, OF MOUNT CARMEL, AND DAVID HARRISON WIGGS, OF DANVILLE,
ILLINOIS

SAFETY DOOR CATCH

Application filed November 14, 1929. Serial No. 407,208.

This invention relates to a safety catch for the heavy sliding doors of railway baggage and express cars, and more particularly to improvements in the safety catch forming 5 the subject matter of our co-pending application filed May 25, 1929, and serially numbered 365,967.

The safety catch disclosed in said application comprises a channel attaching bar 10 adapted to receive and be secured to the upper ends of the door posts of a car, a keeper in the form of a toothed bar secured to the attaching bar, a bolt in the form of a dog adapted to be pivotally mounted on the door 15 of the car and yieldingly held in engagement with the keeper, and means for retracting the bolt and adapted to be operated without the aid of a key from the inside or outside of the car. The bolt and keeper 20 operate to hold the door in partly or fully opened position against accidental closing so as to prevent the loss of life and injuries which so frequently occur as the result of the accidental closing of such doors. The 25 bolt and keeper also cooperate to hold the door in closed position against accidental opening and to permit the accidental movement of the door from a partly opened position in the direction of its fully opened 30 position.

The present invention has for one of its objects to improve and simplify the general construction of the safety catch and to provide one by means of which the door, in addition to being positively held against accidental movement from its fully closed or 35 fully opened position, will be positively held against accidental movement from a partly opened position in the direction of its fully opened or closed position to the end that all possibility of the loss of life and injuries will be avoided.

The present invention has for a further object to provide a safety catch by means 40 of which the doors of various types of rail-

way baggage and express cars may be held against accidental opening and closing movements.

The present invention has for a further object to provide a safety catch wherein the bolt retracting means shall be of such construction as to prevent its operation from outside of the car except by a key.

The present invention has for a still further object to provide a safety catch wherein in the channel bar shall be provided on the interior thereof with elements adapted to permit it to function as the keeper of the catch and wherein this keeper shall be adapted to permit different type bolts to be 55 used.

With the foregoing and other objects in view, the nature of which will appear as the description proceeds, the invention consists in the construction, combination and arrangement of parts hereinafter fully described and claimed, and illustrated in the accompanying drawing, wherein:—

Figure 1 is a view in side elevation of a fragmentary portion of a railway baggage 70 or express car having the door thereof equipped with a safety catch constructed in accordance with our invention;

Figure 2 is a sectional view taken on the vertical planes indicated by the line 2—2 75 of Figure 1;

Figure 3 is a view partly in elevation and partly in vertical section illustrating the manner in which the keeper is adapted to be secured to the door posts;

Figure 4 is a view in side elevation of a fragmentary portion of the keeper illustrating the different positions in which the bolt engaging pins may be arranged therein;

Figure 5 is a perspective view of a slightly modified form of the bolt;

Figure 6 is an elevational view of a further modified form of the bolt;

Figure 7 is a view illustrating a slightly modified form of the means for connecting 80

the bolts of Figures 1, 2 and 5 to the door, and

Figure 8 is a sectional view through the bolt and its supporting means shown in 5 Figure 7.

Referring in detail to the drawing, 1 designates a side, 2 the door posts, and 3 the sliding door of a railway baggage or express car, the door being mounted by means, 10 not shown, for movement to the left while being opened.

The safety catch comprises a keeper 4 which is of channel or inverted U-form in cross section. The keeper 4 receives the upper end portions of the door posts 2, and is secured to the door post by bolts 5. To permit of its ready application to the door posts 2, the keeper 4 is delivered for application with the terminal portions of one of its flanges 6 arranged in horizontal alignment with its web 7, as shown in Figure 3. After the application of the keeper 4 to the door posts 2, these flange portions 6^a are bent downwardly into contact with the door posts, and after this has been done, the bolts 25 are applied.

The keeper 4 is provided on the interior thereof with pins 8 with which the bolt 9 cooperates to secure the door 3 against accidental movement from any position which it may occupy. The pins 8 extend transversely of the keeper 4, and are arranged in relatively spaced relation in the direction of the length of the keeper. Any desired or required number of the pins 8 may be employed, and they may be arranged centrally between the upper and lower edges of the keeper, as shown in Figure 1 or in one of the positions 8^a, 8^b or 8^c, as shown in Figure 40. When the pins 8 are arranged in the position 8^a, a keeper of the maximum effective depth is provided, when they are arranged in the position 8^c, a keeper of the minimum effective depth is provided, and when they are arranged in either of the other positions, a keeper of intermediate effective depth is provided.

The keeper 4 occupies a position above the door 3, and the door moves in a vertical plane situated slightly outward of the plane occupied by the outer flange 6 of the keeper. To support it for movement into and out of the keeper 4 without danger of engaging the flanges 6 thereof, the bolt 9 is slidably mounted upon a spacing or filler block 10 secured to the inner side of the door 3. The bolt 9 is secured to the block 10 for vertical movement with respect to the keeper 4 and pins 8, and the means for securing it to the block may consist of a screw 11 carried by the block and passing through a vertically elongated slot 12 formed in the bolt. The bolt 9 is normally maintained in raised or active position by a spring 13 which is arranged within the slot 12 and bears at its

lower end against the pin 11 and at its upper end against the upper wall of the slot. The bolt 9 may be connected to the block 10 by a dovetail rib 14 formed thereon and mounted in the dovetail slot 15 formed in the block, as shown in Figure 7. When the bolt 9 is connected to the block 10 in this manner, it is normally maintained in active position by a spring 16.

The bolt 9 is provided in its upper edge 75 with a notch 17 and the lugs 17^a formed by the notch have their upper ends inclined downwardly and outwardly, as at 17^b. The bolt 9 is normally engaged with the keeper 4, and it may engage one or a pair of the pins 8. When it is in engagement with a pair of pins 8, the bolt 9 occupies a position between the pins. When the bolt 9 is in engagement with one of the pins 8, the pin engaged occupies the notch 17 of the bolt.

As the bolt 9 may engage one or a pair of the pins 8, the door 3 may be opened to any desired or required extent. The beveled end portions 17^b of the bolt 9 enables the door 3 to be moved in the direction of its fully opened or fully closed position when the bolt is not sufficiently retracted to carry the said end portions fully below the path of the pins 8. The bolt 9 will, when in engagement with one or a pair of the pins 8, hold the door against 90 accidental movement when in fully closed or fully opened position and against accidental movement in opposite directions when in partly opened position.

Means by which the bolt 9 may be retracted or withdrawn from engagement with the keeper 4, comprises a pull rod 18 which is pivotally connected at its upper end, as at 19, to the dog and is connected at its lower end to a cam 20 carried by a spindle 21 journaled in the door 3. The pull rod 18 is connected to the cam 20 through the medium of a yoke 22, the yoke and cam being of such construction as to permit the bolt 9, after it has been retracted and released, to be returned to its projected position by the spring 12. The pull rod 18 is of sectional formation and the sections 18^a and 18^b thereof are connected by a turnbuckle 23 which permits the effective length of the rod to be varied. The spindle 21 is provided with collars 24 and 25 which contact with the inner and outer surfaces of the door 3 and support the spindle against tilting movement in the bearing opening 26 provided therefor in the door. The cam 20 is provided with a circular flange 27 which constitutes a knob through the medium of which the spindle 21 may be turned to effect the retraction of the bolt 9.

The knob flange 27 is located at the inner side of the door 3, and if desired, a spindle turning loop 28 may be used in place thereof, the loop when used being pivoted to the spindle. The outer end 29 of the spindle 21 is of angular formation to permit the re- 130

traction of the bolt 9 from outside of the car only through the medium of a baggage car key which is provided with a socket for the reception of the angular outer end of the spindle.

In Figure 5, a modified form of the bolt is shown. This bolt 9^a differs from the bolt 9 in that it is provided at its upper end with the reduced extension 30 instead of the notch 17. The bolt extension 30 is adapted to engage the keeper 4 at a point between any pair of the pins 8. To facilitate the easy engagement of the bolt extension 30 with the pins 8, the upper end of the extension is 15 pointed, as at 30^a. If desired, the pivoted bolt shown in Figure 6 may be used in place of a sliding bolt. When used, the pivoted bolt 31 is secured to the door 3 by a bracket 32 and is connected to the upper end of the 20 pull rod 18 by a pin 33. The bolt 31 is provided with an angular end 34 which is adapted to engage between any pair of the pins 8. One lateral side of the bolt end 34 is arcuate, as at 35, and the other lateral face 25 thereof is straight, as shown at 36. The upper and lower faces of the bolt end 34 are inclined, as at 37. The formation of the bolt end 34 is such as to permit it to readily engage between a pair of the pins 8, such as to 30 permit it to be readily withdrawn from engagement with the pins, and such as to positively hold the door against accidental movement in opposite directions. The pivoted bolt 31 is pivoted intermediate its ends, as 35 at 38, to the bracket 32, and its is normally maintained in projected position by a spring 39.

If desired, the keeper 4 may be applied to the door post with its open side uppermost, 40 and when it is mounted in this position, the dog shown in our co-pending application may be employed. In order to prevent injury to the pull rod 18 and to the turnbuckle 23, a guard 40 is provided for these parts, the 45 guard being secured to the car door 3.

It should be apparent from the foregoing description, taken in connection with the accompanying drawing, that the safety catch will positively hold the door, when in fully 50 open or fully closed position or when in partly opened position, against accidental movement, that the bolt may be freely retracted from inside the car, and that the bolt may be only retracted from outside of the car 55 through the medium of a key.

It will be further understood that the safety catch is simple and durable, is capable of being manufactured and installed at comparatively low cost, is capable of efficient use 60 on baggage and express cars of different constructions, and is positive and quick in action.

While we have described the principle of our invention, together with the structure which we now consider the preferred embodiment thereof, it is to be understood that the

structure shown is merely illustrative and that such changes may be made, when desired, as fall within the scope of the invention as claimed.

We claim:—

1. A catch for a slidably mounted door, comprising a keeper adapted to be secured across the upper portion of the door opening, the keeper being of channel formation with its open side facing downwardly, metal pins arranged in spaced relation within and extending across the keeper, a bolt adapted to be mounted upon the door for engagement with the pins to secure the door in closed position or in an opened position against accidental movement in opposite directions, and means releasably holding the bolt in pin engaging position. 70

2. A catch for a slidably mounted door, comprising a keeper adapted to be secured across the upper portion of the door opening, the keeper being of channel formation with its open side facing downwardly, metal pins arranged in spaced relation within and extending across the keeper, a bolt adapted 75 to be mounted upon the door for engagement between a pair of the pins to secure the door in closed position or in an opened position against accidental movement in opposite directions, and means releasably holding the bolt in pin engaging position. 80

3. A catch for a slidably mounted door, comprising a keeper adapted to be secured across the upper portion of the door opening, the keeper being of channel formation with its open side facing downwardly, metal pins arranged in spaced relation within and extending across the keeper, a bolt adapted to be mounted upon the door for movement toward and away from the keeper, the upper end of the bolt being adapted to engage between a pair of the pins and provided with a notch adapted to receive one of the pins to secure the door in closed position or in an opened position against accidental movement in opposite directions, and means releasably holding the bolt in pin engaging position. 100

105

4. A catch for a slidably mounted door, comprising a keeper adapted to be secured across the upper portion of the door opening, the keeper being of channel formation with its open side facing downwardly, metal pins arranged in spaced relation within and extending across the keeper, a bolt adapted 110 to be mounted upon the door for movement toward and away from the keeper, the upper end of the bolt being adapted to be engaged between a pair of the pins to secure the door in closed position or in an opened position against accidental movement in opposite directions, the upper end of the bolt being provided with beveled portions adapted to facilitate its engagement between a pair of the pins, and means yieldingly holding the bolt 115 in pin engaging position. 120

125

5. A catch for a slidably mounted door, comprising a keeper adapted to be secured across the upper portion of the door opening, the keeper being of channel formation with its open side facing downwardly, metal pins arranged in spaced relation within and extending across the keeper, a bolt adapted to be mounted upon the door for movement toward and away from the keeper, the upper end of the bolt being provided with beveled portions adapted to facilitate its engagement between a pair of the pins, and means yieldingly holding the bolt 130 in pin engaging position.

5. A catch of the character set forth, including a keeper having parallel flanges and a web connecting the flanges, terminal portions of one of the flanges being arranged in alinement with the web and bendable from said position into alinement with the intermediate portion of such flange, and pins terminally secured to the flanges between said terminal portions.
10. In testimony whereof we hereunto affix our signatures.
